UNITED STATES PATENT OFFICE.

EUGENE RENAUD, OF MONTREAL, QUEBEC, CANADA.

COLLAR BUTTON.

Application filed November 12, 1923. Serial No. 674,321.

To all whom it may concern:

Be it known that I, EUGENE RENAUD, a subject of the King of Great Britain, residing at Montreal, Province of Quebec, Canada, have invented certain new and useful Improvements in Collar Buttons; and I do hereby declare that the following is a full, clear, and exact description of the invention, such as will enable others skilled in the art 10 to which it appertains to make and use the same.

The present invention pertains to a novel collar button designed particularly for use in connection with men's wear.

15 The principal object of the invention is the provision of a device of this character which affords secure attachment between a pair of articles of clothing usually held together by a collar button passed through 20 buttonholes in both garments. In order to accomplish this object the device comprises a back member on which is formed a pair of prongs. The latter are disposed in planes substantially parallel to that of the back, and point in opposite directions. In applying this device to a buttonhole, one of the 25 prongs is first passed through the hole, and the entire device is turned until the remaining prong reaches the hole. This remaining 30 prong is then caused to pass through the hole by a slight pressure thereon by the finger of the wearer.

The invention is fully disclosed in the following description and in the accompanying 35 drawings in which:

Figure 1 is a perspective view of the improved collar button;

Figure 2 is an elevation thereof;

Figure 3 is an end view;

40 Figure 4 is a perspective view of the back buttonhole in a shirt band, showing the collar button applied thereto; and,

Figure 5 is a similar view showing the collar in place.

45 Reference will now be had to these views by means of like characters which are employed to designate corresponding parts throughout.

50 The improved collar button comprises essentially a back 1 which is curved to conform to the neck of the wearer. At one edge of the back is formed a pair of prongs

2 of substantially right angular configuration, as shown in Figures 1 and 3. In other words, each prong comprises a stem 3 perpendicular to the back 1 and a head 4 which is perpendicular to the stem and substantially parallel to the back. The heads point in opposite directions, as is evident from any one of the figures.

55 In Figure 4 is illustrated a shirt generally designated by the numeral 5 and provided with the customary collar band 6. In the band is formed a buttonhole 7. When the collar button is to be applied, it is inserted beneath the collar band, and one of the prongs is passed through the buttonhole. The device is now turned until the remaining prong reaches the hole and passes therethrough if a slight pressure of the 60 finger is applied. In order to facilitate the entrance of the prongs into the buttonhole, the heads 4 are rounded at the sides, as shown by the numeral 8. The collar 9 is applied to the buttonhole in the reverse 65 manner to that described. The buttonhole 10 is passed over one of the prongs, and the collar is slightly turned until the buttonhole is in position to receive the remaining prong. Obviously, the remaining prong 70 75 80 may be passed through the buttonhole by turning in the manner described in connection with Figure 4, if this method of application is found to be preferable.

85 While a specific embodiment of the invention has been illustrated and described, it is to be understood that various alterations in the details of construction may be made without departing from the spirit of the invention as indicated by the appended claim.

90 Having thus fully described the invention, what I claim as new and desire to protect by Letters Patent is:—

95 A collar button comprising a back, a pair of stems formed thereon and lying in a plane substantially perpendicular to that of the back, heads extending from said stems and lying in a plane substantially parallel to that of the back, said heads pointing in opposite directions, the side edges of said 100 heads being rounded.

In witness whereof I have hereunto set my hand.

EUGENE RENAUD.
